UNITED STATES PATENT OFFICE

2,442,162

ROVING CATCHER

Wolcott H. Bussiere, Pittsfield, Mass.

Application November 29, 1947, Serial No. 788,892

3 Claims. (Cl. 57—107)

1

This invention relates to improvements in spinning apparatus and is directed more particularly to improvements in apparatus for catching and breaking roving or yarn as it is wound onto a bobbin when the roving or the yarn is heavier or coarser than desired.

In United States Letters Patent No. 2,428,064, issued to me on September 30, 1947, there is shown and described apparatus for use in connection with a spinning frame which is adapted to catch and break a roving or yarn as it is wound onto the bobbin, when the roving or yarn is too heavy or coarse, and the principal object of this invention is the provision of an improved device for catching and breaking the roving.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a side elevational view of a roving catcher embodying the novel features of the invention;

Fig. 2 is a perspective view of the control lever of the catcher shown in Fig. 1; and

Fig. 3 is a front elevational view of a plurality of the catchers of the invention associated with a longitudinal bar.

Referring now to the drawings more in detail, the invention will be fully described.

The roving catcher of the invention includes a supporting bracket 2 having forward and rear depending spaced arms 4 and 6.

The arm 4 of the bracket may be secured as by bolts 8 to a longitudinal bar 10. Said bar may be such a bar as 26 in the above identified patent.

A catcher 14 is slidable back and forth in the arms 4 and 6 and has a head 16 on its forward end. A spring 18 around the catcher urges it forwardly and a stop 20 which may be a cotter pin or the like in the catcher limits forward movements of the catcher.

A lock 22 is freely slideable in a guide 24 secured to the bracket 2 and it has an upper head 26.

The member 14 is provided with a seat 28 which receives the lower end 22' of the lock 22.

A control lever 30 is pivoted at 32 to the bracket 2 for swinging in a horizontal plane. The forward end 34 of the lever is adapted to project beyond the member 4 and it has a vertical inner

2

end part 36 adapted to underlie the head 26 of lock 22.

The upper edge 38 of the part 36 is cam shaped or concave as clearly shown in Fig. 2. This cam is arranged so that when the central portion of the cam portion underlies the head 26 of the lock the lower end 22 of the lock is seated in the seat 28 of the member 14 and holds the said member 14 against the action of spring 18 in the rear or retracted position shown in Fig. 1. When the lever 30 is swung in one direction or the other, the cam elevates the lock so that the member 14 is released whereupon it is moved forwardly by the spring 18 to its outer or extended position, shown by dash lines.

With the catcher secured to a support such as 10 or some other part of a spinning frame which will locate the catcher adjacent a bobbin, the roving or yarn as it is wound onto the bobbin loops outwardly.

Coarse or heavy yarn loops outwardly to a greater extent than relatively lighter or finer yarn.

The coarse yarn strikes the end 34 of the control lever to swing it so that the cam 38 of arm 36 elevates lock 22 whereby the catcher is extended by the spring 18. Then the heavy yarn catches on the member 14 and is broken as is desired.

By swinging the control lever to its normal position, the member 14 may be moved inwardly so that the lock 22 drops into the seat 28 to hold the catcher in retracted position.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

45 What it is desired to claim and secure by Letters Patent of the United States is:

1. A yarn catching and breaking device for a spinning machine comprising in combination, a support for securing to a spinning machine, a catcher slidable back and forth in said support between forward breaking and rear positions, means urging said catcher to breaking position, lock means slidably in said support engageable with means provided on said catcher to releasably hold said catcher in rear position, and means

swingable on said support to release said lock means and adapted to be engaged by yarn for swinging to act on and release said lock means.

2. A yarn catching and breaking device for a spinning machine comprising in combination, a support for securing to a spinning machine, a catcher slideable in said support between forward yarn catching and rear positions, a spring urging said catcher to forward position, and means holding said catcher in rear position, said means including a lock movable between locking and releasing positions engageable with a seat provided on said catcher and a lever engageable by yarn swingable to move said lock to releasing position whereby said catcher is urged forwardly by said 15. spring.

3. A yarn catching and breaking device for a spinning machine comprising in combination, a support for securing to a spinning machine, a catcher slideable in said support between forward 5. and rear positions, a spring urging said catcher to forward position, a lock slideable in said support between locking and non-locking position, said catcher having a seat therein which said lock is receivable when in rear position whereby said catcher is held in rear position, a lever swingable on said support adapted to be engaged by yarn and engageable with and adapted to move said lock to non-locking position.
